UNITED STATES PATENT OFFICE

2,579,335

REFRIGERATOR CRISPER

George L. Pownall, Cincinnati, Ohio

Application August 31, 1949, Serial No. 113,338

6 Claims. (Cl. 62—80)

1

This invention relates to closed containers for use in refrigerators, the closed containers being of the type usually referred to as "crispers" or "hydrators" and being adapted for storing fresh vegetables or the like in a humid atmosphere. More particularly, this invention relates to a device for the proper and more healthful preservation of fresh food stuffs in the so-called household mechanical refrigerators, and more specifically to the closed containers as currently being used for the storage of fresh vegetables and fruits, commercially known as "crispers," "hydrators," "humidrawers," etc.

In the past, and also present day, manufacturers of household mechanical refrigerators have furnished portable closed containers for the storage of fresh vegetables and fruits within the refrigerator cabinet. The occasion calling for the use of these closed containers is the well known fact that the mechanical units dry out and dehumidify the food products, accordingly, they have resorted to a closed container attempting to overcome this objection.

This applies to all mechanical refrigerators, whether of the type with the evaporator suspended within the cabinet, or those having evaporator coils built-in within the walls of the cabinet, which are commercially known as "cold wall" refrigerators, and this invention is applicable to either and all types of mechanical refrigerators.

With the adoption of the closed container the manufacturer, or supplier, created a very unhealthy situation for the storage of these fresh food products, as confined air within the closed container soon becomes polluted with gases given off by the food products which results in an accelerated rate of decomposition. Furthermore, due to the difference of temperature between the outside and inside of the closed container it resulted in further dehydration of the fresh food stuffs as indicated by droplets of water extracted from the food stuffs and appearing on the underside of the closed container cover lid.

It is a purpose of this invention to overcome and eliminate this unhealthy situation, and to positively remove bacteria from within the closed container food compartment to remove the pollution of the bacteria infested air by supplying cleansed, washed, humidified and thermally circulated air to create a fresher air condition.

Another object is the external application of required refrigerating effect to the closed container while simultaneously setting up internally

2

of the container a thermal flow of air currents to purify the air contained therein.

Another object is the flow of cleansed, washed, humidified air between the food storage compartment and the air conditioning chamber of the closed container.

Another object is the internal isolation and entrapment within the closed container of the polluted meltage water resulting from the air cleansing action.

Another object is the elimination of foul, stagnant air conditions ordinarily found in closed containers.

Another object is the absorption of the foul, polluted air and gases as given off by the food stuffs in the closed container.

Another object is the elimination of wastage and losses of food products stored in the closed container.

Another object is the provision of a simple and expedient apparatus for attaining the above objects.

The conventional crisper is kept moist or humid by the water extracted from the contents of the crisper. It is therefore a further object of this invention to provide means for supplying added moisture to the crisper in order to maintain a humid atmosphere therein.

Briefly, this invention provides a crisper which is divided by an upright partition into a main or storage compartment and a secondary or humidifying compartment. The humidifying compartment in turn may be divided into upper and lower compartments or sections. The upper section serves as an ice holder and the lower as a sealed isolated water trap section.

In the upper section of the humidifier compartment, ice particles such as the conventional ice cubes formed in a mechanical refrigerator may be placed. The upper section of the humidifier compartment and the main compartment of the crisper are in communication so that air can circulate between the compartments. However, the lower section of the humidifier compartment is isolated from the upper section thereof and from the main compartment. Ice meltage drains into the lower section of the humidifier compartment where it is segregated from the rest of the crisper and accumulates until discharged. The meltage absorbs the pollution and noxious odors which otherwise would be present in the air within the crisper and removes these undesirable and

noxious materials from the air while concom-

stantly imparting oxygen to the air thereby preserving the freshness of air in the crisper.

The above and other objects and features of the invention will in part be obvious and will in part be apparent from the following detailed description and the drawings, in which:

Figure 1 is a perspective view showing a mechanical household refrigerator containing a crisper constructed in accordance with an embodiment of this invention, the refrigerator being shown with the normally closed door thereof in open position;

Fig. 2 is a perspective view, partly broken away and in section, of the crisper illustrated in Fig. 1;

Fig. 3 is a plan view of the lower portion or box of the crisper illustrated in Figs. 1 and 2 with the cover lid removed;

Fig. 4 is a view in section taken along line IV—IV in Fig. 3, the crisper being shown with ice cubes in the upper section of the humidifying or air conditioning compartment;

Fig. 5 is a view in section taken along line V—V in Fig. 3;

Fig. 6 is a view in section taken along line VI—VI in Fig. 5 with the cover lid shown in position;

Fig. 7 is a view in section showing a crisper constructed in accordance with a second embodiment of this invention; and

Fig. 8 is a view in section showing a crisper constructed in accordance with a third embodiment of this invention.

In the following detailed description and the drawings, like reference characters indicate like parts.

In Fig. 1 is shown a mechanically cooled refrigerator 10, which may be of conventional type, having a freezing unit 12. A crisper 13 is placed on a lower shelf of the refrigerator 10.

As shown in Fig. 2, the crisper 13 includes a lower section or compartment which is shaped as an open-topped box or chamber having end walls 16, side walls 17 and 18 and a bottom 19. A top or cover 21 fits over and closes the open top of the crisper chamber. The top 21 is provided with handles 22 at opposite ends for raising the top from the lower portion 14. Finger grips 23 are provided at opposite ends of the box for lifting the crisper from the refrigerator as a unit. A downwardly depending flange 24 on the top fits on a peripheral shoulder 26 about the lower portion of the crisper to form a substantially air-tight seal between the top and the lower portion or chamber of the crisper. The crisper and top may be formed of any suitable material such as glass, plastic material, or porcelain, or the crisper may be constructed of dissimilar materials, such as glass for the top cover lid and porcelain for the main bottom box-like structure, likewise, the means of seating the cover lid on the box-like bottom structure may be by other means to attain a relatively air tight enclosure, such as a bevel seat.

A lengthwise partition 27 divides the lower box-like portion of the crisper into a main storage or food containing compartment 28 and a smaller humidifier compartment adjacent and along the side wall 17. The partition 27 and the adjacent side and end walls are provided with inclined or beveled seats 31, 32, and 32' (Figs. 2 and 4) respectively, which are disposed approximately midway between the bottom wall of the crisper and the top thereof. A transverse partition 33 (Figs. 2 and 4) rests on the beveled seats 31, 32 and 32' dividing the humidifier compartment into

an upper ice-holding section 34 and a lower meltage receiving section 36. The transverse partition 33 forms a substantial seal between the sections of the humidifier compartment. Upright ribs 37 on the transverse partition support ice particles, or cubes, while meltage from the ice particles drains through a tube 39 that depends from the transverse partition.

The tube 39 extends into a well formed by a U-shaped partition 41 which is attached to the side wall 17 and to the bottom of the lower humidifier section. A liquid trap is formed in the well as soon as enough meltage is formed to fill the well to above the bottom of the tube as shown most clearly in Fig. 4. Further meltage fills the well until it overflows into the lower section 36 of the humidifier compartment.

The main partition 27 is apertured, as indicated at 42 above the beveled seat 31, and, as shown in Fig. 6, the partition 27 terminates below the cover of the crisper so that air from the main compartment can pass over the ice particles. Ice meltage from the particles picks up noxious odor bearing materials from the air in the storage compartment and isolates such noxious materials in the lower humidifier section. This action in washing and purifying air and removing bacteria therefrom is explained in greater detail in my Patent 2,527,571, issued Oct. 31, 1950.

The operation of the crisper will be evident from the foregoing detailed description and the drawings.

The crisper is assembled and ice is placed in the upper section of the humidifier compartment while vegetables and the like may be stored in the main compartment 28. The ice can be replenished as it melts until such time as it is necessary to empty meltage from the humidifier compartment. When the humidifier compartment is to be emptied, the top 21 is removed and the humidifier compartment transverse partition 33 is lifted free by means of a handle 43, whereupon meltage can be poured out and the crisper reassembled.

As will be understood, other types of liquid traps may be substituted for the traps shown in Figs. 2 to 6 inclusive. In Fig. 7 is shown a crisper having another form of trap. The crisper shown in Fig. 7 includes a main or box portion 45 divided by a partition 46 into a food storage compartment and a minor humidifying or air conditioning compartment. A transverse partition 47 in the humidifying compartment is adapted to support ice particles. The partition 47 carries a gooseneck pipe or trap 48 that discharges ice meltage into the lower section of the humidifying compartment where the meltage is isolated from the air which can come in contact with food in the storage compartment.

In Fig. 8, a crisper is illustrated which is substantially similar to the crispers shown in the other drawings with the exception that it includes no mechanical trap for the ice meltage. Instead, a transverse partition 49 is provided having alternate rows of ribs 51 and small drainage holes 52, the holes being of such size as to retain droplets of meltage water as long as ice chunks 53 are present and melting upon the transverse partition. The droplets gravitate to the section below the transverse partition as the ice melts, but between drops there is a tendency for the small holes 52 to retain some of the meltage for sealing purposes. Isolation of the contaminated meltage is thereby achieved in a

satisfactory manner. In other respects, the unit shown in Fig. 8 may be similar to those shown in the other drawings.

The ice serves to keep air in the crisper humid and fresh, for it maintains humidity in the crisper without removing moisture from the contents thereof, and meltage from the ice removes noxious materials given off by the contents of the crisper and isolates these materials in the enclosed lower section of the humidifying compartment. In addition, the ice cools the air as the air passes over the ice, causing the air to circulate through the food storage compartment and the upper section of the humidifier compartment.

In the foregoing detailed description and the drawings, the crisper has been described and shown as a portable unit, but it is to be understood that the crisper could be a built-in feature provided arrangements are made for evacuating the polluted meltage water.

The crisper of this invention is subject to other structural modification without departing from the spirit and scope of the appended claims.

Having described my invention, what I claim as novel and desire to secure by Letters Patent is:

1. A refrigerator crisper which comprises an open-topped box, a substantially air-tight lid for said box, an upright main partition in said box dividing the box into a storage compartment and a humidifier compartment, a transverse partition in the humidifier compartment dividing the humidifier compartment in to a lower enclosed water trap section and an upper ice holding section, the partition in the humidifier compartment being adapted to support ice particles, the upper part of the main partition being apertured to permit circulation of air between the storage compartment and the upper section of the humidifier compartment, a conduit for discharging ice meltage from the upper section of the humidifier compartment to the lower section thereof, and a water-sealing trap between the sections of the humidifier compartment to isolate the meltage in the lower section from air in the upper section of said humidifier and from the storage compartment.

2. A refrigerator crisper in accordance with claim 1 characterized by the fact that the partition between sections of the humidifier compartment is removable, that a tube depends from the humidifier compartment partition and is adapted to drain meltage from the upper section of the humidifier compartment, and that the tube is adapted to extend substantially to the bottom of the box to form a trap adapted to be sealed by water in the lower section of the humidifier compartment.

3. A refrigerator crisper in accordance with claim 1 characterized by the fact that the partition between sections of the humidifier compartment is removable, that a tube depends from the humidifier compartment partition and is adapted to drain meltage from the upper section of the humidifier compartment, that a well extends upwardly from the bottom of the box inside the lower section of the humidifier compartment, that the tube is adapted to extend into the well to form a trap between sections of the hu-

midifier compartment adapted to be sealed by water in the well, and that the well is open at its upper end to permit meltage to overflow from the well into the lower section of the humidifier compartment.

4. A refrigerator crisper which comprises a hollow box, an upright main partition in said box dividing the box into a storage compartment and a humidifier compartment, a transverse partition in the humidifier compartment dividing the humidifier compartment into a lower enclosed water trap section and an upper ice holding section, means in the ice holding section for supporting particles of ice, the upper part of the main partition being apertured to permit circulation of air between the storage compartment and the upper section of the humidifier compartment, means for discharging ice meltage from the upper section of the humidifier compartment to the lower section thereof, and a water-sealing trap between the sections of the humidifier compartment to isolate the meltage in the lower section from air in the upper section of the humidifier compartment and in the storage compartment.
5. A refrigerator crisper which comprises a hollow open-topped box, a substantially air-tight lid for said box, an upright main partition in said box dividing the box into a storage compartment and a humidifier compartment, a transverse partition in the humidifier compartment dividing the humidifier compartment into a lower enclosed water trap section and an upper ice holding section, the storage compartment and the upper section of the humidifier compartment being in communication to permit circulation of air therebetween, means for discharging ice meltage from the upper section of the humidifier compartment to the lower section thereof, and a water-sealing trap between the sections of the humidifier compartment to isolate the meltage in the lower section from air in the upper section of the humidifier compartment and in the storage compartment.

6. A refrigerator crisper which comprises a hollow open-topped main box, a substantially air-tight lid for said box, and a humidifier box inside said main box, said humidifier box comprising a hollow lower enclosed meltage isolating section and an upper ice holding section, the upper section being in communication with the interior of the main box to permit circulation of air therebetween, means for discharging ice meltage from the upper section of the humidifier box to the lower section thereof, and a water sealing trap between sections of the humidifier box to isolate the meltage in the lower section from air in the upper section and in the main box.
